UNITED STATES PATENT OFFICE.

BENJAMIN J. RYAN, OF DALLAS, TEXAS.

MACHINE FOR FORMING GARMENT HANGERS.

Application filed January 3, 1922. Serial No. 526,466.

To all whom it may concern:

Be it known that I, BENJAMIN J. RYAN, a citizen of the United States, residing at Dallas, in the county of Dallas and State of Texas, have invented certain new and useful Improvements in Machines for Forming Garment Hangers, of which the following is a specification.

This invention relates to new and useful improvements in machines for forming garments hangers.

The object of the invention is to provide a manually operated machine of inexpensive construction involving certain novel features.

Among the novel features are wire bending arms, co-operating with wire forming and guide pins and a deflector involving a simplified structure; together with simple and practical means for twisting the ends of the wire and forming a hook on one of the ends.

Still another feature resides in foot-operated mechanism arranged to undergo a limited movement, but to impart to the wire bending arms a swing sufficient to effect their operation.

A construction designed to carry out the invention will be hereinafter described together with other features of the invention.

The invention will be more readily understood from a reading of the following specification and by reference to the accompanying drawings, in which an example of the invention is shown and wherein:

Fig. 1 is a plan view of a machine constructed in accordance with my invention, showing in dotted lines the manner in which a piece of wire is bent by the wire bending arms.

Fig. 2 is a cross-sectional view taken on the line 2-2 of Fig. 1.

Fig. 3 is an underside view of the central portion of the table, showing means for swinging the wire bending arms.

Fig. 4 is an enlarged detail of the hook forming device,

Fig. 5 is an enlarged detail of the hook forming elements in their operative position,

Fig. 6 is an enlarged detail of one of the wire bending arms,

Fig. 7 is an enlarged longitudinal sectional view of the wire twisting device,

Fig. 8 is an enlarged face view of the wire twisting head,

Fig. 9 is a plan view of the arm shown in Fig. 6,

Fig. 10 is an enlarged detail of one of the arm swinging pulleys,

Fig. 11 is a sectional view of the pulley taken on the line 11-11 of Fig. 10, and

Fig. 12 is an enlarged detail of a finished garment hanger formed by the machine.

In the drawings the numeral 10 designates an elongated table supported by suitable legs 11 at each end. Disposed in spaced relation along the rear portion of the table are corresponding wire bending arms 12 with integral ears 13 at their inner ends. The ears are fixed to vertical posts 14 which extend above the same and thru the table, said posts being loosely confined in suitable apertures, whereby the wire bending arms are pivoted. As is best shown in Figs. 6 and 7, the upper edge of each arm extends above the ear throughout its length, while the outer ends of the arms are bent forwardly and provided with wire receiving notches 15. When the arms are in normal position, as is shown in Fig. 1, it will be seen that a straight piece of wire 16 may be placed longitudinally of the arms so as to lie in the notches 15 and to rest on the said ears between the posts 14 and the inner edges of the arms. As is shown in Fig. 1, the ends of the wire are broken away; however, it

is to be understood that the wire is disposed so that one end projects farther from the end of the table than the other, whereby a long and a short end of the wire are formed when the arms 12 are swung forwardly. Guide brackets 16' are spaced apart and mounted on the table intermediate the posts 14, so as to engage the rear edge of the wire and prevent the latter from bowing when the arms 12 are swung.

Mounted on the front central portion of the table are upright forming pins 17, while a pair of guide pins 18 are mounted intermediate the pins 17. An elongated vertical deflector blade 19 has its rear end pivoted in a suitable bracket 20 secured to the table, and is directed between the guide pins

18 in close proximity to the same. The forward lower edge of the deflector is curved upwardly, while the deflector is adapted to be swung upwardly upon its end, as is shown in dotted lines in Fig. 2.

For operating the wire bending arms 12, I mount a split pulley 21 on the lower end of each pivot post 14, as is shown in Fig. 3. A belt 22 extends from pulley to pulley, and has each end coiled partially round a pulley with its extremity secured in the joint of the sections thereof. A flexible connection 23 attached to the belt intermediate its ends extends forwardly over a vertical pulley 24. Mounted on each side of the center of the table is a roller 25, over which the belt is drawn by the connection 23. As is best shown in Fig. 2, the connection depends from the pulley 24 and is fastened to a foot lever 26 which extends forwardly and is hinged to a member 27 secured to the underside of a cross bar 28 extending between the rear legs 11. A suitable treadle 29 is mounted on the forward end of the lever 26, and it will be seen that by depressing the latter with the foot, the pulleys undergo a rotating movement, whereby the arms 12 are swung forwardly. In order that the said arms may return automatically to their normal position when the lever 26 is released, I provide a coiled spring 30 in the hub 31 of each pulley. As is shown in Fig. 11, each spring surrounds a post 14 and has one end secured thereto, while the other end is embedded in the table. It is evident that when the foot lever 26 is depressed, said springs are wound under tension, and it is obvious that when said lever is released, the unwinding action of the springs causes the wire bending arms to swing to their normal position. Although I have illustrated and described the preferred means of operating the wire bending arms, it is to be understood that the invention is not limited thereto, and that any other practical means may be employed for this purpose.

When the arms 12 are swung forwardly, it will be seen that the wire is bent round the posts 14, and that the ends of the wire strike the sides of the deflector 19, while the outer curved ends of the arms press the wire against the pins 17 and 18, whereby the ends are deflected forwardly, as is shown in dotted lines in Fig. 1. Upon this operation it will be seen that a long and a short end are formed, the next operation being to twist the latter upon the former to provide a neck for the hanger.

For this purpose I provide a wire twisting device comprising a sliding bar 31, slideable in guides 32 provided on the underside of the table. The outer end of the bar has a bearing post 33, journaled in which is a tubular shaft 34 provided with a crank han-

dle 35 on its outer end. The shaft is slideable in the post and has an enlarged head 36 directed toward the forward end of the deflector 19. The face 37 of the shaft is concave and is in alinement with the forwardly directed ends of the wire, said face having an oblong slot 38 in its center for receiving said ends. An elongated lug 39 projects from the underside of the head toward the inclined portion of the deflector.

By sliding the bar 31 inwardly with considerable force, the ends of the wire are received in the shaft, while the lug 39 strikes the inclined edge of the deflector and swings the latter upwardly to a position as is shown in dotted lines in Fig. 2. Upon this operation the head 36 strikes the extreme outer ends of the arms 12 which causes the wire to be pressed firmly against the pins 17 and 18. It will be readily seen that by revolving the shaft 34 by the crank handle 35, the short end of the wire is twisted together with the long end, thus providing a neck 40 (as is shown in Figs. 5 and 12) and leaving the long end extending forwardly. The bar 31 may then be slid outwardly, as is shown in Figs. 1 and 2, and the foot lever 26 released, whereby the wire bending arms 12 are swung to their normal position by the action of the springs 30.

The table is provided with a forward extension 41 at one end, pivoted to which is an arm 42. The outer end of the arm carries a hook forming device, comprising a bushing 43, loosely confined upon which is a roller sleeve 44. A washer 45 is placed on top of the bushing to prevent upward displacement of the sleeve. A pin 46 passes thru a lever 47 and the said washer, and is screwed into the bushing. One end of the lever has a depending finger 48, while a suitable handle 49 is provided on the other end. As is best shown in Fig. 4, a space is left between the depending finger and the roller sleeve. The arm 42 is of such length as to permit the hook forming device to receive the long end of the wire between the said finger and roller sleeve, when the arm is swung inwardly. As is pointed out in Fig. 5, by moving the lever 47 a quarter-turn to the left the wire is bent at an acute angle to the neck, while a substantial rotation of the lever to the right bends the wire round the roller sleeve and forms a hook. This operation completes the hanger and the same may be easily lifted off the machine, a specimen of a hanger formed by a machine embodying the invention being shown in Fig. 12. After the hanger has been removed from the machine, it is obvious that the arm 42 may be swung to an outward position, as is shown in Fig. 1.

It is pointed out that a machine constructed in accordance with my invention embodies an inexpensive and simplified structure.

The machine includes simple and efficient mechanism for operating the wire bending arms, as well as means for forming a neck and hook on the hanger, and it will be seen that garment hangers may be produced expeditiously by such a machine.

Various changes in the size and arrangement of the different parts, as well as modifications may be made without departing 10 from the spirit of the invention.

What I claim, is:

1. In a wire forming machine, a support, a pair of swinging wire forming arms having their adjacent ends pivoted on the support and adapted to engage and bend a wire, forming projections carried by the support and over which the wire is bent by the arms, a deflector blade mounted on the support and co-operating with the arms to bend the 15 free ends of the wire outwardly, a wire twisting device slidably mounted to engage and twist the ends of the wire upon themselves, said wire twisting device being provided with means for displacing the deflector blade from between the ends of the wire, and a hook forming device comprising a swinging support carrying a hook forming element arranged to receive one of the ends of the wire and form the same into a hook 20 when rotated in reverse directions.

2. In a wire forming machine, a support, a pair of swinging wire forming arms having their adjacent ends pivoted on the support and adapted to engage and bend a wire, forming projections carried by the support and over which the wire is bent by the arms, a deflector blade mounted on the support and co-operating with the arms to bend the free ends of the wire outwardly, a wire 25 twisting device slidably mounted to engage and twist the ends of the wire upon themselves, said wire twisting device being provided with means for displacing the deflector blade from between the ends of the wire, and a hook forming device comprising a swinging support carrying a hook forming element arranged to receive one of the ends of the wire and form the same into a hook when 30 rotated in reverse directions, and means for operating the said arms.

3. In a wire forming machine, a support, a pair of swinging wire forming arms having their adjacent ends pivoted on the support and adapted to engage and bend a wire, forming projections carried by the support and over which the wire is bent by the arms, a deflector blade mounted on the support and co-operating with the arms to bend the free ends of the wire outwardly, a wire twisting device slidably mounted to engage and twist the ends of the wire upon themselves, said wire twisting device being provided with means for displacing the deflector blade from between the ends of the wire, a hook 45 forming device comprising a swinging sup-

port carrying a hook forming element arranged to receive one of the ends of the wire and form the same into a hook when rotated in reverse directions, and means connected with the arms for swinging the same forwardly, said means including a member for automatically swinging the arms in a reverse direction after an operation.

4. In a wire forming machine, a support, a pair of swinging wire forming arms adapted to engage and bend a wire, forming projections carried by the support and over which the wire is bent by the arms, a deflector blade mounted on the support and co-operating with the arms to bend the free ends of the wire outwardly, a wire twisting device slidably mounted to engage and twist the ends of the wire upon themselves, said wire twisting device being provided with means for displacing the deflector blade from between the ends of the wire, a hook forming device comprising a swinging support carrying a hook forming element arranged to receive one of the ends of the wire and form the same into a hook when rotated in reverse directions, pulleys connected with the said arms, and a flexible element partially wound upon the pulleys and having connection with a foot lever, said pulleys adapted to be rotated by the unwinding action of the element when said lever is depressed, whereby said arms are swung forwardly.

5. In a wire forming machine, a support, a pair of swinging wire forming arms adapted to engage and bend a wire, forming projections carried by the support and over which the wire is bent by the arms, a deflector blade mounted on the support and co-operating with the arms to bend the free ends of the wire outwardly, a wire twisting device slidably mounted to engage and twist the ends of the wire upon themselves, said wire twisting device being provided with means for displacing the deflector blade from between the ends of the wire, a hook forming device comprising a swinging support carrying a hook forming element arranged to receive one of the ends of the wire and form the same into a hook when rotated in reverse directions, pulleys connected with the said arms, a flexible element partially wound upon the pulleys and having connection with a foot lever, said pulleys adapted to be rotated by the unwinding action of the element when said lever is depressed, whereby said arms are swung forwardly, and a resilient member connected with the arms and adapted to swing the same in an opposite direction when the foot lever is released.

6. In a wire forming machine, a support, a pair of swinging wire forming arms adapted to engage and bend a wire, forming projections carried by the support and over which the wire is bent by the arms, a de-

deflector blade mounted on the support and co-operating with the arms to bend the free ends of the wire outwardly, the lower edge of the forward end of said blade being inclined, a wire twisting device slidably mounted to engage and twist the ends of the wire upon themselves, said wire twisting device comprising a slidable bar having a bearing post on its outer end, a tubular shaft 10 slidable in the post and provided with a crank handle on its outer end, the opposite end of the shaft having an enlarged head directed toward the deflector blade and an opening for receiving the ends of the wire, 15 and a lug projecting from the underside of the head and adapted to strike the inclined edge of the deflector blade and displace the latter from between the ends of the wire, and a hook forming device comprising a 20 swinging support carrying a hook forming element arranged to receive one of the ends of the wire and form the same into a hook when rotated in reverse directions.

7. In a wire forming machine, a support, 25 a pair of swinging wire forming arms adapted to engage and bend a wire, forming projections carried by the support and over which the wire is bent by the arms, a deflector blade mounted on the support and co- 30 operating with the arms to bend the free ends of the wire outwardly, the lower edge of the forward end of said blade being inclined, a wire twisting device slidably mounted to engage and twist the ends of the wire 35 upon themselves, said wire twisting device comprising a slidable bar having a bearing post on its outer end, a tubular shaft slidable in the post and provided with a crank handle on its outer end, the opposite end of the 40 shaft having an enlarged head directed toward the deflector blade and an opening for receiving the ends of the wire, and a lug projecting from the underside of the head and adapted to strike the inclined edge of 45 the deflector blade and displace the latter from between the ends of the wire, and a hook forming device comprising a swinging support carrying a stationary element at its free end, a roller sleeve loosely confined on

the element, a lever mounted on top of the 50 element and pivoted thereto, said lever having a finger depending from one end parallel to the roller sleeve, the hook forming device being adapted to receive one of the ends of the wire between the said finger and sleeve 55 and form the same into a hook when the said lever is rotated in reverse directions.

8. In a wire forming machine, a support, a pair of swinging wire forming arms adapted to engage and bend a wire, forming projections carried by the support and over which the wire is bent by the arms, a deflector blade mounted on the support and co-operating with the arms to bend the free ends of the wire outwardly, the lower edge 65 of the forward end of said blade being inclined, a wire twisting device slidably mounted to engage and twist the ends of the wire upon themselves, said wire twisting device comprising a slidable bar having a bearing post on its outer end, a tubular shaft 70 slidable in the post and provided with a crank handle on its outer end, the opposite end of the shaft having an enlarged head directed toward the deflector blade and an 75 opening for receiving the ends of the wire, and a lug projecting from the underside of the head and adapted to strike the inclined edge of the deflector blade and displace the latter from between the ends of the wire, a 80 hook forming device comprising a swinging support carrying a stationary element at its free end, a roller sleeve loosely confined on the element, a lever mounted on top of the element and pivoted thereto, said lever having a finger depending from one end parallel to the roller sleeve, the hook forming device being adapted to receive one of the ends of the wire between the said finger and sleeve 85 and form the same into a hook when the said lever is rotated in reverse directions, and means connected with the said arms for swinging the same forwardly, said means including a member for automatically swinging the arms in a reverse direction 90 after an operation.

In testimony whereof I affix my signature.
BENJAMIN J. RYAN.
